APPARATUS FOR CONTROLLING DRAFT

Robert R. McIntosh, Battle Creek, Mich.

Application January 26, 1942, Serial No. 428,262

16 Claims. (Cl. 110—147)

The present invention relates broadly to the regulation of draft, and in its specific phases it relates to methods and apparatus for use in controlling the induced draft created in railway locomotive smoke boxes.

The creation of draft in railway locomotives, according to standard practice, involves the direction of exhaust steam from the cylinders up the smoke stack to create a partial vacuum in the smoke box at the front end of the locomotive. In order to induce draft when the locomotive is standing or drifting, a live steam blower is mounted below the smoke stack and adapted to deliver live steam up through same. The draft produced due to the delivery of exhaust steam up the smoke stack varies among other things with the per cent cut-off at which the locomotive is operated, as well as with the frequency and volume of exhaust from the cylinders, other factors remaining constant. Operation in this manner according to standard practice results in pulsating extreme variations in draft suction pressures which, at the higher suction pressures, carries small cinders and burning coal particles from the fire-box and blows them out through the smoke stack, a thing which not only creates dirt, fuel loss, and a fire hazard, but abrasively wears out the tubes, superheater units, and front end surfaces exposed to the flow of gases containing these particles. Such practice also causes uneven burning of fuel, dilution and cooling of the products of combustion, and wastes heat due to too rapid flow of the products of combustion from the fire-box to the front end of the locomotive.

The detrimental effect of excessive and fluctuating suction in the smoke box has been recognized by those familiar with locomotive construction and operation. In an effort to partially compensate for these disadvantages while maintaining the beneficial effect of induced draft, the practice has grown up of installing partitions and baffle plates in the smoke box so as to restrict the flow areas and thus partially control the rate of flow of products of combustion to and into the smoke stack. It has also been standard practice to supplement such partitions and baffles with a netting to hold back and break up the larger cinders and burning pieces of coal drawn out of the fire-box and through the tubes due to excessive draft suction. Still further restrictions in flow areas have been created by large ignition arches in the fire-box thereby cutting down the flow area between the top of the arch and the crown sheet. The use of partitions, baffle plates,

and netting is of some beneficial aid in holding the suction pressures within closer limits, but this still leaves undesirable fluctuations of same and requires higher suction pressures in front of the baffles to overcome the effect of the restrictions. The obtaining of these higher suction pressures requires the employment of higher steam exhaust back pressures on the cylinders, a thing which in turn reduces the horsepower output of the locomotive. Higher suction in the smoke box above combustion requirements also automatically requires a higher fuel firing rate to utilize the excess air drawn into the fire-box of the locomotive, and this, coupled with dilution, not only increases fuel consumption, but also decreases the efficiency of conversion of heat into power. The few solutions attempted for this problem took into consideration the fundamental need of induced draft, but failed to do more than downwardly displace and partially control the suction pressure range as a whole at the front tube sheet. This left the original inherent drafting problem unsolved prior to my discoveries in the drafting field and which are embodied in my copending patent application, Ser. No. 381,290, filed March 1, 1941. In that application, I set forth the broad method of multiple level drafting together with specific forms of apparatus for accomplishing same. Broadly, the drafting therein described involves the admission of controlled amounts of auxiliary air into the smoke box when the draft therein would normally exceed a predetermined pressure level, such pressure level also being variable in accordance with the drafting demands of the locomotive. My present invention involves the modification, simplification, and improvement of my aforementioned invention.

Accordingly, among the objects of the present invention is the provision of a simplified method and apparatus for automatically controlling, at a plurality of levels, the suction pressures utilized in producing induced draft.

Another object is to provide a plurality of air inlet means adapted to open and admit suitable amounts of air into a smoke box or the like at predetermined suction pressure levels therein for maintaining the corresponding level when the pressure would normally raise above same, the lower suction pressure level air inlet means having in conjunction therewith a releasable means for gripping same in closed position when a predetermined higher suction pressure level is required.

Another object is to provide means for con-

trolling the air inlet means so as to maintain a low suction pressure level in the smoke box under low percent cut-off or fuel feed, and to automatically raise the suction pressure level when a predetermined higher percent cut-off or fuel feed is reached.

A further object is to provide automatic and/or manual control of the suction pressure levels in the smoke box.

A further object is to provide improved locomotive drafting which will permit all or a major portion of the baffles in the locomotive smoke box to be removed, the length of the ignition arches to be reduced, and to eliminate need of the netting which is now used to stop burning fuel particles from being discharged through the smoke stack.

A further object is to provide a drafting apparatus mountable in the locomotive smoke box in manner permitting ready inspection of the front tube sheet and front ends of the tubes, and the removal of superheater units, without the necessity of removing partitions, baffle plates, netting, or the like.

A further object is to provide a drafting apparatus adapted to normally hold the induced suction pressure in the smoke box at moderate, predetermined, and relatively uniform levels, free from excessive pulsations, so that particles carried by the products of combustion from the firebox to the smoke box will be of light weight and either completely burned out before reaching the smoke box or quickly burned out in the air admitted to the smoke box, all before the particles pass out of the latter.

Still further objects and advantages of the present invention will appear as the description proceeds.

To the accomplishment of the foregoing and related ends, the invention, then, consists of the steps and means hereinafter fully described and particularly pointed out in the claims, the annexed drawings and the following description setting forth in detail certain means and modes of carrying out the invention, such disclosed means and modes illustrating, however, but several of the various ways in which the principle of the invention may be used.

In said annexed drawings:

Figure 1 is a side elevation of a locomotive front end embodying one form of the present invention, and with a portion of the smoke box shell removed to show the location of some of the parts therein.

Figure 2 is a partially sectioned elevational view taken along line 2-2 of Figure 1, and with draft suction pressure control mechanisms diagrammatically illustrated in connected position.

Figure 3 is an enlarged center section view of a valve disc as viewed along line 3-3 of Figure 5 and looking in the direction of the arrows.

Figure 4 is a fragmentary elevational view of the valve operating cam assembly looking in the direction of the arrows along line 4-4 of Figure 2.

Figure 5 is a top view of a valve assembly looking in the direction of the arrows along line 5-5 of Figure 2.

Figure 6 is a side elevation of a locomotive front end embodying another form of the present invention.

Figure 7 is a partially sectioned elevational view taken along line 7-7 of Figure 6, and with manual as well as a modified form of automatic control mechanism shown diagrammatically in enlarged size and in connected position.

Figure 8 is an elevational assembly, on reduced scale, looking in the direction of the arrows along line 8-8 of Figure 7.

Figure 9 is a top view of a modified valve operating assembly looking in the direction of the arrows along line 9-9 of Figure 8.

Figure 10 is a partially sectioned elevational assembly of one form of valve particularly adapted for use as shown in Figures 7 and 8.

Figure 11 is a partially sectioned elevational view similar to Figure 2, showing in diagrammatic manner electrical control for use in shifting pressure levels in the smoke box.

Figure 12 is a partially sectioned elevational view similar to Figure 7, showing in diagrammatic manner electrical controls for use in shifting pressure levels in the smoke box.

Referring more particularly to Figures 1 and 2 of the drawings, the locomotive 1 has a smoke box 2 with a conventional door 3 at its front end for use in inspecting or repairing the various parts mounted within the smoke box or accessible therethrough. An exhaust stand 4 with nozzle 5 is connected in conventional manner to the exhaust outlet from the driving cylinders (not shown). Directly above exhaust stand 4 is smoke stack 6 which has a depending extension 7 with a flared bottom 8 which is commonly referred to as a petticoat. The delivery of exhaust steam 30 through smoke stack 6 from nozzle 5 of exhaust stand 4 creates suction in the locomotive smoke box when the locomotive is under motion. The suction or draft thus produced is transmitted through the locomotive boiler tubes (not shown) 35 to the fire-box (not shown) to facilitate combustion of fuel therein. A blower ring 9 conventionally connected for delivery of live steam up smoke stack 6 is utilized for creating a mild draft when the locomotive is standing or drifting.

Mounted within the locomotive box, in the construction shown in Figure 2, are a pair of air inlet assemblies 10 and 11. For ease of removal of these assemblies, they are preferably connected respectively to tubular members 12 and 13 by means of flange connections 14 and 15. The outer end of each of these tubular members 12 and 13 extends into or through a suitable opening in the side of the smoke box and are welded or otherwise joined thereto so as to form a substantially air tight joint. For purposes of closing the outer ends of these tubular members in case of temporary removal or breakage of an air inlet assembly, gates 16 and 17 are provided, and these gates are respectively mounted for sliding action 55 on suitable ways 18 and 19.

Referring more particularly to air inlet assembly 10 as shown in Figures 2 and 5, this assembly preferably utilizes an elbow 20 with its inner end turned upward and with the face thereof approximately in a horizontal plane. The upper edge of this elbow is preferably in the form of a wide flange 21 which has been suitably faced to provide a relatively level surface to facilitate making a sealed joint as will be hereinafter explained. Mounted within elbow 20 and adjacent the upper end thereof is a spider 22 with a central enlargement 23 which acts as a bearing permitting endwise sliding of rod 24 which may have a head 25 on its lower end. Mounted on the upper end of rod 24 is a disc valve 26 with a packing ring 27 suitably fastened on the under face of same and adapted to seal on the upper face of flange 21. This packing ring must be suitable to resist the heat in the smoke box and make a good seal when valve 26 is in lowermost position.

Woven strip asbestos packing which is approximately $1\frac{1}{4}$ " x $\frac{1}{4}$ " and riveted at 2" centers to the face of disc 26 has been found well suited for this purpose. In order to help stabilize disc valve 26 in its up and down movements, suitable openings 28 and 29 (Figure 3) may be provided in same. Passing through these openings are guide rods 30 and 31 which are conventionally fastened on flange 21 and may be respectively provided, if desired, with heads 32 and 33 which act as upper limit stops so far as the movement of the disc valve 26 is concerned. If desired, heads 32 and 33 may be eliminated and head 25 on rod 24 utilized for the same purpose. Air inlet assembly 11 is preferably of identical construction to that of air inlet assembly 10 and accordingly detailed description of same will be omitted to avoid duplication.

The constructing and mounting of air inlet assemblies so that the disc valve moves in a vertical direction, simplifies the construction of same and does away with the need of pulleys and cables carrying weights, or like means which are necessary to normally hold a horizontally movable, vertically mounted, disc valve in place. In actual operation, disc valve 26 and the parts which move in unison therewith are made of a suitable total weight to permit same to move upward and admit air into the interior of the smoke box when the suction pressure therein reaches and slightly exceeds the pressure level at which this assembly is set to open. When the fuel feed to the locomotive fire-box exceeds a predetermined moderate rate, or the steam being admitted to the cylinders is delivered under a cut-off in excess of a predetermined amount, the amount of fuel to be burned under these conditions is greater and accordingly the draft level should be higher. To take care of this situation, air inlet assembly 10 may be set at the upper draft level required to meet these conditions, while air inlet assembly 11 may be set to open at a predetermined lower suction pressure level suitable for use with lower rates of fuel feed or cut-off settings. In other words, in operating under the latter conditions, air inlet assembly 11 will control the lower suction pressure level in the smoke box, and air inlet assembly 10 will be adapted to control the upper suction level for conditions of operation under higher percentage of cut-off, and/or increased rates of fuel feed.

In order to shift the suction pressure level in the smoke box from the lower level to the higher level, air inlet assembly 11 is releasably held in closed position, thus allowing the higher suction pressure level air inlet assembly 10 to function alone. Where the suction pressure level is to be controlled in accordance with the per cent cut-off at which the locomotive is operating, the suction pressure levels may be readily controlled by means of the apparatus diagrammatically illustrated in Figure 2. In this construction a suitable size cylinder 34 is conventionally mounted on the front end of the locomotive. This cylinder is provided with a conventional piston 38 connected to a piston rod 35 with depressor head 36 on its lower end directly over the center of disc valve 26a. A guide member 37 for piston rod 35 may be provided for stability of the latter if desired. This assembly may be operated by means of live steam or compressed air, although the latter is preferably used since locomotives normally carry their own air compressor systems and the use of compressed air eliminates the necessity of traps and drains which would be required to

remove condensate in case steam were utilized for this purpose. Compressed air is delivered through main line 38 to reducing valve 39 and thence by means of pipe 40 to cylinder 34 below the piston slidably mounted therein. The air pressure thus delivered to cylinder 34 acts to normally hold the piston rod assembly in upper position and allows air inlet assembly 11 to function at the lower suction pressure level. Main line 38 is also connected by means of pipe 41 to valve 42 the outlet of which in turn is connected by pipe 43 to the upper end of cylinder 34. The locomotive is provided in conventional construction with at least two driving cylinders 99, each of which has a housing 100 for the cut-off valve 101 which is diagrammatically illustrated and may be of various types. The cut-off valves in this case are connected through link 11 in conventional manner to cut-off control lever 44. The inlet and exhaust of steam from cylinders 99 are handled through conventional piping (not shown).

Cut-off control lever 44 (Figures 2 and 4) has a plate 45 welded or otherwise fastened thereto. Adjustably mounted on plate 45 by means of cap screws or studs 46 is an arcuate cam member 47 which is slotted for adjustment. Under actual operating conditions, the per cent cut-off at which the suction pressure level is to be shifted from the lower to the higher is chosen and then arcuate cam member 47 adjusted so that when the percentage of cut-off is in excess of the chosen shifting point the arcuate cam member 47 will actuate valve 42 and cause the delivery of compressed air through pipe 43 into the upper end of cylinder 34. Since the latter pressure is in excess of the pressure delivered from reducing valve 39 through pipe 40 into the lower end of cylinder 34, the piston rod assembly will be moved downward so that depressor head 36 will contact disc valve 26a and hold same against upward movement. This allows air inlet valve assembly 10 to control the suction pressure level in the smoke box. To facilitate the operation of cylinder 34 and movement of piston rod 35, a pressure releaser 48 is connected to pipe 40 and set to open at a pressure considerably less than the main line pressure but somewhat greater than the pressure delivered through pressure reducing valve 39. Where the main line air pressure is approximately one hundred and ten pounds per square inch, a convenient pressure delivered through reducing valve 39 is twenty-eight pounds per square inch and the pressure releasing valve 48 may be set at a pressure just in excess of that delivered by pressure reducing valve 39 in order to relieve the back pressure caused by downward movement of the piston, although I prefer to set the pressure releasing valve at approximately fifty pounds per square inch since this provides a cushioning effect which makes the assembly work more smoothly. It is to be noted, however, that there is no particular limitation as to the exact pressures or size of cylinder to be used so long as the principles herein expressed are utilized and the pressure exerted upon disc valve 26a is sufficient to hold same closed when the suction pressure is to be maintained at a higher level, for instance, that at which air inlet assembly 10 is set to operate. In this connection, the apparatus may also be manually operated, for instance, by means of opening and closing valve 49. Both manual and automatic operation may be utilized in this manner, or if the manual oper-

ation alone is desired, then valve 50 may be closed.

The controlling of the suction pressure level in the smoke box may also be accomplished in conventional manner in accordance with the rate of fuel feed. For instance, as is shown in Figure 2, valve 51 which may be used to control the flow of steam to the locomotive stoker engine, or to control the flow of oil where same is used as fuel, may be connected by means of a suitable link 52 to valve 53 so that the operation of valve 51 through lever 54 will automatically operate valve 53 and control the movement of piston rod 35. Link 52 in this case would preferably be provided with a lost motion connection so that lever 54 would have to move to increase the fuel feed to a predetermined point before valve 53 would open to change the suction pressure level from low to high. A suitable spring 55 may be used to hold valve 53 in closed position under normal operating conditions when the fuel feed is below the predetermined transition point. The control of the suction pressure level through the fuel feed may be omitted, used alone, or in conjunction with other control means, several of which have been typically described.

A typical valve suitable for use in connection with the cut-off cam members is shown in partial section in Figure 10. The steam or air used for operating this valve is delivered to the lower end of same through pipe 41 into compartment 56, the outlet of which is closed by means of a spring projected ball bearing 57 in contact with a suitable seat. Directly above ball bearing 57 is a compartment 58 to which is connected outlet pipe 43. In contact with the upper face of ball bearing 57 is a push rod 59 which carries a check valve 60. This check valve is movable in compartment 51 which has a vent opening 62. A supporting member 63 carries pivot pin 64 on which is pivotally mounted depressor arm 65. Mounted on the upper end of this arm is shaft 66 which in turn carries cam shoe contacting roller 67. Depressor arm 65 is provided with a downwardly opening cavity 68 containing a compression spring 69 and a slidable closed bottom cup member 70, the lower end of which in turn contacts the upper end of push rod 59. The whole assembly is conventionally mounted on platform 71.

In the operation of valve 42, the movement of arcuate cam member 47 (Figures 2 and 4) into contact with and over roller 67 will move push rod 59 downward under the cushioning influence of spring 69, and this downward movement in turn will depress spring projected ball bearing 57 and allow fluid to flow under pressure from compartment 56 into cavity 68 and hence out through pipe 43 to the upper end of cylinder 34. The depressing of push rod 59 at the same time moves check valve 60 downward to close the lower end of compartment 51 and substantially prevent leakage therethrough. When arcuate cam member 47 is moved out of contact with roller 67, push rod 59, under the influence of spring projected ball bearing 57, moves upward and the outlet from compartment 56 is sealed. At the same time, check valve 60 moves upward to the position shown in Figure 10, and this allows fluid in pipe 43 to flow backward into compartment 56 and thence through compartment 51 and a small vent opening 62 to the atmosphere to permit quick release operation of the piston rod assembly which has been gripping disc valve 26a in closed position. Vent

opening 62 and the connections leading thereto may be made relatively small, if desired, so that it will not interfere with the simultaneous operation of the suction pressure level control either manually or through the use of the fuel feed control. The placing of valve 50 in pipe 43 instead of pipe 41 will of course make possible the independent operation of either manual control or fuel feed control of the suction pressure levels, but under such conditions, valve 50 should be of the type which has a small vent to allow slow leakage of fluid from the side thereof connected to cylinder 34, since otherwise in the absence of a suitable pressure relief means the release of pressure in cylinder 34 for return of the system to the lower suction pressure level would be difficult and very slow at best.

Instead of using a two-level suction pressure system, the apparatus may be arranged for more than two levels, for instance, a three-level system as diagrammatically shown in Figure 7. The invention, however, is not limited to the use of two or three levels but rather is broadly directed to multiple level controls wherein the principles herein set forth are utilized. A convenient way of installing the pressure level assemblies is to connect tubular inlet members 12a and 13a to an open ended tubular cross member 72. For convenience of description and illustration, but without being limited thereto, the low suction pressure inlet assembly 73 has been shown at the left in Figure 7, while the upper suction pressure inlet assembly 74 has been shown in the middle and the intermediate suction pressure inlet assembly 75 at the right. Since these inlet assemblies are preferably identical with that described in connection with Figure 2, detailed description of same will be omitted to avoid duplication. Disc valve 26b in this case will be suitably weighted to open at the predetermined upper suction pressure level, for instance, at a suction pressure of approximately 5½ inches of water. Under these conditions, intermediate pressure disc valve 26c may be weighted to open at a suction pressure of 5½ inches of water, and low suction pressure disc valve 26d at 4½ inches of water. It is to be noted at this point that the invention is not limited to these specific suction pressures, but rather they are used only by way of example to facilitate the description and understanding of the present invention. The controlling of the air inlet suction pressure level assemblies may be accomplished in various ways as has been typically described in connection with the two-level assembly shown in Figure 2. However, to save duplication of description, the operation of the three-level assembly shown in Figure 7 will be described only in terms of variations in accordance with cut-off settings as supplemented by independent mechanical control. The main operating fluid, which ordinarily will be either live steam or air under pressure, although preferably the latter as has been hereinbefore described, is delivered to the control system through main line 38. Connected to main line 38 is a reducing valve 39, the outlet of which is connected to pipe 40a. This pipe in turn is connected to the lower ends of cylinders 34a and 34b, wherein it acts to normally hold the pistons 3a and 3b at the upper end of each of these cylinders. A pressure release valve 48 is connected in pipe 40a at the outlet side of reducing valve 39. This valve 48 is set to operate at a pressure somewhat in excess of the pressure at which reducing valve

39 has been adjusted, as has been described above. When the suction pressure level in the smoke box is to be held at the low level, for instance 4½ inches of water, then the low suction pressure inlet assembly 73 will be free to open and allow air to flow from tubular member 72 therethrough into the smoke box. When it is desired to raise the suction pressure to the intermediate level, for instance, 5½ inches of water, the controlling apparatus operates to move piston rod 35a downward until depressor head 36a holds disc valve 26d of the low pressure inlet assembly in closed position. Under these conditions the intermediate suction pressure air inlet assembly 75 will function to admit air into the smoke box from tubular member 72 when the suction pressure in the smoke box reaches the intermediate level. To further increase the suction pressure to the upper level, for instance, 5¾ inches of water, the controlling apparatus operates to move piston rod 35b downward until depressor head 36b clamps disc valve 26c of the intermediate pressure assembly into closed position. Under these conditions, the low pressure inlet assembly 73 and the intermediate pressure assembly 75 will both be held in closed position so that the upper suction pressure level assembly 74 will then control the inlet of air from tubular member 72 into the smoke box at the predetermined upper suction pressure level.

The controlling of the clamping of the disc valves of the low and intermediate pressure level air inlets through the actuation of the cut-off mechanism may be accomplished in various ways and one of the most convenient will now be described. The reverse arm 76 of the locomotive has a link 77 which is suitably connected to the valve gear which actuates the main steam valve (not shown) of one of the driving cylinders so as to control the cut-off of steam admitted thereto. The reverse arm 76 is mounted and keyed on a cross shaft 78 on the other end of which is mounted and keyed another reverse arm (not shown) for operating a like cut-off control of the main steam valve for the driving cylinder on the opposite side of the locomotive. Reverse arm 78 therefore moves forward and back in accordance with the movement of the cut-off setting controls in the locomotive cab (not shown). The increasing of the cut-off under forward travel of the locomotive results in reverse arm 78 being moved in clockwise direction as viewed in Figure 8. To take advantage of this for controlling the air inlet assemblies, a plate 79 with arcuate flange 80 may be anchored to the side of reverse arm 76 in conventional manner, for instance, by means of screws 81. Under these conditions, the arc of flange 80 is set so that its center is on the center line of cross shaft 78. Flange 80 is provided with slots 82 through which extend studs or cap screws 83 which in turn are fastened to cam shoe members 84 and 85. Assembling the cam shoes on arcuate flange 80 in this manner permits adjustment of the shoes to various cut-off settings and hence in combination with valves 42a and 42b governs the shifting of the suction pressure levels in the smoke box.

Mounted on the frame 86 of the locomotive is an anchor bracket 87 on which are mounted valves 42a and 42b. Rollers 67a and 67b respectively of these two valves are adapted to engage cam shoe members 84 and 85. For instance, cam shoe 84 may be adjusted to engage and depress rollers 67a at cut-off settings of thirty per cent

and more. This engagement in turn will cause low pressure air inlet assembly 73 to be held in closed position. Cam shoe member 85 in turn may be adjusted so as to engage and depress roller 67b at cut-off settings of forty per cent and more so that under these conditions, intermediate pressure air inlet assembly 75 will be held in closed position, thus allowing the upper pressure air inlet assembly 74 to function. In other words, the low pressure inlet assembly 73 controls the suction pressure level up to thirty per cent cut-off, at which point this assembly is gripped shut and the inlet pressure increased to that controlled by intermediate pressure inlet assembly 75. This assembly controls the inlet pressure until the cut-off is increased to forty per cent, at which point this assembly is gripped shut and held in that position along with inlet assembly 73. Under these conditions upper section pressure assembly 74 controls the suction pressure for all cut-off settings above forty per cent. It is to be understood that the specific cut-off percentages noted are used as illustrative of the operation of this apparatus, and are not to be considered as a limitation on the invention since obviously other cut-off settings can be used so long as the principles herein set forth are utilized.

The low pressure level may also be manually controlled by opening valve 88 which will deliver air to the upper end of cylinder 34a and cause disc valve 26d to be clamped down. The intermediate pressure level may be controlled manually in like manner through the operation of valve 89, the opening of which will likewise deliver air to the top of cylinder 34b and cause disc valve 26c to be held down in closed position. Valves 88 and 89 may be placed in the locomotive cab (not shown), and if desired, both manual and automatic operation of the draft levels may be utilized.

Instead of using a fluid such as steam or air for shifting the suction pressure level in the smoke box, this may be accomplished electrically, for instance, as diagrammatically shown in Figures 11 and 12. These two figures have been patterned after Figures 2 and 7 respectively for simplicity of illustration and description. Referring to Figure 11, air inlet assembly 11a utilizes a disc valve 26e which has a projecting rod 91 anchored to the upper face thereof and extending into solenoid 92. The upper portion of rod 91 is suitably constructed for use as the movable iron core of this solenoid. Under normal operation, when the low suction pressure level is to be controlled by means of air inlet assembly 11a, disc valve 26e with rod 91 is free to move upward whenever air is required for admission from inlet assembly 11a into the smoke box for maintaining the low pressure level. When the pressure level in the smoke box is to be raised to that controlled by air inlet assembly 10, electric current is passed through solenoid 92. This solenoid is of a suitable size and connected to the electric circuit so as to exert sufficient downward pressure on rod 91 of the disc valve 26e to hold same in closed position throughout the period when the higher suction pressure level is to be maintained.

The operation of solenoid 92 may be controlled in various ways, such as mechanically, in accordance with fuel feed, or cut-off settings. Electric current is delivered to the system from a suitable source, such as an electric generator through wires 93 and 94, one of which, for instance 93, may be connected directly to solenoid 92. Wire 94, on the other hand, is connected by means of

suitable switches to solenoid 92, so as to complete a suitable electric circuit therethrough. Where it is desired to control the operation of solenoid 92 in accordance with settings of the cut-off mechanism, the cut-off control lever 44 may be provided with an arcuate cam member 41 as hereinbefore described. An electric switch 85, preferably of the quick make and break type, is suitably mounted on platform 11 and provided with a pivoted cam contacting arm 86 adapted to be actuated by cam member 41, which has been previously adjusted, so that it will actuate arm 86 and close the circuit through switch 85 at a predetermined cut-off setting. The closing of the circuit through switch 85 automatically delivers current through solenoid 92 so that it exerts downward pressure on rod 91 in manner holding disc valve 26e in closed position. The apparatus may likewise be controlled in accordance with the rate of fuel feed by merely substituting a suitable switch 97 (Figure 11) for valve 53 illustrated in Figure 2. The system may also be manually controlled through the use of a suitable switch 98 which, if desired, may be placed in the locomotive cab (not shown), so that the engineer or fireman may operate same whenever desired.

As shown in Figure 12, the apparatus diagrammatically illustrated in Figure 7 may also be electrically controlled. In this case, main line wire 83 may be connected as previously described, while main line wire 84 is suitably connected through switches or the like to solenoids 92a and 92b, to complete the circuit. These two solenoids in turn control, through rods 91a and 91b, the holding of low pressure disc valve 26f and intermediate pressure disc valve 26g in closed position in accordance with the predetermined suction pressure level to be maintained in the smoke box.

Referring to Figure 12, the electrical controlling of pressure levels in an assembly such as is typically shown in Figure 7, may be readily accomplished, for instance, by shifting the suction pressure level from the low level controlled by disc valve 26f to the intermediate level controlled by disc valve 26g in accordance with cut-off settings. Under these conditions cam shoe member 84 is suitably adjusted on flange 88 of plate 79 so as to close the electric circuit through electric switch 85a at a prescribed setting of the cut-off mechanism, and hold switch 85a in closed position for all cut-off settings which are higher than the one at which switch 85a is closed. The closing of switch 85a delivers current through solenoid 92a which in turn, through rod 91a, delivers downward pressure onto disc valve 26f to hold same closed until such time as disc valve 26f is to be used to again control the suction pressure level in smoke box 2. The operation of solenoid 92a and the closing of disc valve 26f automatically shifts the suction pressure level to that controlled by intermediate pressure level air inlet disc valve 26g. When the cut-off setting has been still further advanced, so that the suction pressure level is to be transferred to that controlled by disc valve 26b, cam shoe 85 will contact and actuate switch 85b so as to deliver electric current through solenoid 92b for all cut-off settings which are higher than the one at which switch 85b is closed. This solenoid will then exert downward pressure through rod 91b to hold air inlet valve 26g in closed position the same as air inlet valve 26f which was previously closed. This automatically leaves disc valve 26b to con-

5 trol the upper suction pressure level in smoke box 2. The reduction of the cut-off settings below those at which switches 85b and 85a were closed will automatically open the respective circuits and release in corresponding order the intermediate pressure level air inlet disc valve 26g and low pressure level air inlet disc valve 26f. These two air inlet disc valves may also be manually controlled. For instance, by closing switch 88a, solenoid 92a will act to hold low pressure air inlet valve 26f in closed position. Similarly the closing of switch 88b will act through solenoid 92b to hold intermediate pressure air inlet valve 26g in closed position. The closing of switch 88a thus shifts the pressure level to be maintained in smoke box 2 from low to intermediate and when this is followed by the closing of switch 88b, the latter will shift the pressure level in the smoke box from intermediate to high, the latter level being controlled by means of disc valve 26b.

10 A locomotive of the 4-8-4 type which in working order, weighs 666,500 pounds, operates on two hundred and fifty pounds per square inch boiler pressure, and which has 60,200 pounds tractive effort, has been equipped with this invention. This locomotive, which is used in regular and continuous high speed manifest freight service, is giving very much improved performance in the elimination of black smoke, and a marked reduction in velocity of the products of combustion over the heating surfaces which has resulted in better combustion and more efficient conversion of heat into power. Additional advantages which have been noted are a reduction 15 in the amount of fuel and water consumed as well as a definite reduction of the cinder cutting of the superheater units, stack, and front end. The draft control of the present invention has substantially eliminated the emission of sparks from the locomotive stack, and has also produced substantially balanced draft throughout the locomotive from the fire bed to the front end thereof. The installation of this draft control has further made it possible to operate with larger air 20 openings through the grate than formerly utilized, thereby confining changes in draft to closer and lower limits and increasing the life of the grate bars.

25 Other modes of applying the principle of my invention may be employed instead of those explained, change being made as regards the means and steps herein disclosed, provided those stated by any of the following claims or their equivalent be employed.

30 I therefore particularly point out and distinctly claim as my invention.

35 1. In an apparatus for controlling suction pressure at least at one predetermined level in a compartment, the combination which comprises means for creating suction pressure in said compartment, said suction pressure normally rising above said predetermined level if not controlled, means including a suitable size closeable inlet for admitting a suction reducing gaseous fluid into said compartment when said suction pressure rises to said predetermined level, means for controlling the amount of said suction reducing gaseous fluid admitted into said compartment so as to hold said suction pressure from rising substantially above said predetermined level, means for gripping said closeable inlet into closed position when a higher suction pressure is to be maintained in said compartment, and means for controlling the operation of said gripping means and releasing said closeable inlet when the suction

pressure level in said compartment is to be again controlled by same.

2. In an apparatus for controlling suction pressure in a compartment, the combination which comprises means for creating suction pressure in said compartment, said suction pressure normally rising to undesired high levels unless controlled, a plurality of inlets to said compartment, means for admitting at least through one of said suction pressure level control inlets to said compartment a suction reducing gaseous fluid in amount sufficient to hold said suction pressure from rising substantially above a set suction pressure, there being at least one of said inlets for each pressure level, and means for gripping each lower suction pressure level inlet in closed position when raising the suction pressure in said compartment to a higher level and releasing said inlets when lowering the suction pressure in said compartment, the extent of said controlled lowering of the suction pressure being governed by the lowest pressure controlling inlet released.

3. In an apparatus for controlling draft suction pressure through a locomotive, the combination which comprises means for creating draft in a locomotive smoke box, means for admitting at one of a plurality of inlets to said smoke box a suction reducing gaseous fluid in amount sufficient to hold said draft suction pressure from rising substantially above a set suction pressure, there being a definite normal opening pressure for each of said inlets, and means for gripping each lower suction pressure level inlet in closed position when raising the suction pressure to a higher level and releasing at least one of said inlets when lowering the suction pressure.

4. In an apparatus for controlling the draft suction pressure through a locomotive, the combination which comprises means for utilizing exhaust steam from the locomotive driving cylinders to create suction pressure in a locomotive smoke box, means for admitting a suction reducing gaseous fluid into said smoke box when said suction pressure rises to a predetermined level, the amount of said suction reducing gaseous fluid admitted to said smoke box being controlled in manner to hold said suction pressure from rising substantially above said predetermined level, and means for automatically changing said suction pressure level at which said second gaseous fluid is admitted into said smoke box in accordance with predetermined variations of cut-off settings of the valves admitting live steam to the locomotive driving cylinders.

5. In an apparatus for controlling draft suction pressure through a locomotive, the combination which comprises means for creating draft in a locomotive smoke box, means for admitting a suction reducing gaseous fluid into said smoke box in amount sufficient to hold said draft suction pressure from rising substantially above a set suction pressure level, and means for automatically changing the set suction pressure from one level to another in accordance with changes in draft requirements.

6. In an apparatus for controlling draft created in a locomotive smoke box, the combination which comprises means for utilizing exhaust steam from the locomotive driving cylinders to create a suction pressure in said smoke box, means for admitting a suction reducing gaseous fluid into said smoke box in amount sufficient to hold said draft suction pressure from rising substantially above any one of three predetermined set suction pressure levels, and means for automatically chang-

ing the suction pressure in the smoke box from one level to another of the three in accordance with predetermined variations of cut-off settings of the valves admitting live steam to the locomotive cylinders.

7. The combination with a smoke box and means for creating draft suction pressure therein, of valve means adapted to automatically open to admit a suction pressure reducing fluid, such as air, into said smoke box when the suction pressure therein reaches a predetermined level and automatically close when said suction pressure drops below said predetermined level, a second valve means constructed for operation in like manner to the first, but at a higher predetermined suction pressure level, and a releasable means for use in the shifting of the suction pressure control from the first valve means to the second and back in accordance with which predetermined upper suction pressure in the smoke box is chosen for the admission of suction reducing gaseous fluid, said releasable means being adapted to grip the low pressure inlet valve in closed position when the higher predetermined suction pressure level is to be maintained.

8. The combination with a smoke box and means for creating draft suction pressure therein, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first but at a higher predetermined suction pressure level, releasable means for gripping the low pressure inlet valve in closed position, and means for operating said releasable means and thus shifting the suction pressure control from the first valve means to the second and back in accordance with which predetermined upper suction pressure in the smoke box is chosen for the admission of suction reducing gaseous fluid.

9. The combination with a smoke box and means for creating draft suction pressure therein, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first but at a higher predetermined suction pressure level, releasable means for gripping the low pressure inlet valve in closed position, and means for operating said releasable means and thus shifting the suction pressure control from the first valve means to the second and back in accordance with which predetermined upper suction pressure in the smoke box is chosen to control the admission of suction reducing gaseous fluid, said means for operating said releasable means including a cylinder with piston and piston rod mounted in position so that the extending of the piston rod from said cylinder in accordance with movement of the piston therein will cause the low pressure inlet valve to be gripped in closed position, and upon movement of the piston in the opposite direction will release said inlet valve, and means for controlling the supply of operating fluid to said cylinder.

10. The combination with a smoke box and means for creating draft suction pressure there-

in, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first but at a higher predetermined suction pressure level, releasable means for gripping the low pressure inlet valve in closed position, and means for operating said releasable means and thus shifting the suction pressure control from the first valve means to the second and back in accordance with which predetermined upper suction pressure in the smoke box is chosen to control the admission of suction reducing gaseous fluid, said means for operating said releasable means including an electrically operated member, a means suitably mounted in position so that the application of force thereto through the actuation of said electrically operated member will cause the low pressure inlet valve to be gripped in closed position and upon removal of said force said inlet valve will be released for normal operation, and means for controlling the supply of electricity to said electrically operated member.

11. The combination with a smoke box and means for creating draft suction pressure therein, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first, but at a higher predetermined suction pressure level, a projectible member for gripping the low pressure valve in closed position, means for moving said projectible member into valve gripping position, and means for controlling the means which moves said projectible member into valve gripping position so that said low pressure valve may be gripped into closed position and subsequently released, whereby the suction pressure level in the smoke box may be shifted from the low pressure level to the higher pressure level and back in accordance with which predetermined upper suction pressure in the smoke box is chosen for the admission of suction reducing gaseous fluid.

12. The combination with a locomotive having driving cylinders, cut-off means controlling the inlet of steam to said cylinders, a smoke box, and means for creating draft suction pressure in the latter, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first, but at a higher predetermined suction pressure level, a projectible member for gripping the low pressure valve in closed position, means for moving said projectible member into valve gripping position, and means actuated by the setting of the per cent cut-off for the admission of steam to the locomotive driving cylinders to automatically control the movement of said projectible member into gripping position with the low pressure inlet valve to hold same closed when the per cent cut-off exceeds a predetermined amount, and release same when the percent cut-off is below that amount, whereby

the suction pressure level in the smoke box will be automatically increased to the level permitted by said second valve means when the per cent cut-off exceeds a predetermined amount, and such level automatically lowered to that permitted by the first valve means as soon as the percent cut-off drops below said predetermined amount.

13. The combination with a locomotive having a fire box, means for feeding fuel to said fire box, a smoke box, and means for creating draft suction pressure in the latter, of valve means adapted to automatically open to admit a suction pressure reducing gaseous fluid, such as air, into said smoke box, when the suction pressure therein reaches a predetermined level, and automatically close when said suction pressure drops below said predetermined level, a second valve means constructed for operation in like manner to the first, but at a higher predetermined suction pressure level, a projectible member for gripping the low pressure valve in closed position, means for moving said projectible member into valve gripping position, and means actuated by the fuel feeding means to automatically control the movement of said projectible member into gripping position with the low pressure inlet valve to hold same closed when the rate of fuel feed exceeds a predetermined amount and release same when the fuel feed is below that amount, whereby the suction pressure level in the smoke box will be automatically increased to the level permitted by said second valve means when the rate of fuel feed exceeds a predetermined amount, and such level automatically lowered to that permitted by the first valve means as soon as the rate of fuel feed drops below said predetermined amount.

14. The combination with a smoke box and means for creating draft suction pressure therein, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first, but at a higher predetermined suction pressure level, a projectible member for gripping the low pressure valve in closed position, a cylinder, a piston movable in said cylinder, said piston being connected to said projectible member, valve including means connected to said cylinder at the opposite side of said piston from that at which said projectible member extends and adapted to deliver a gaseous fluid thereto under suitable pressure, and means for normally holding said piston and projectible member in retracted position.

15. The combination with a smoke box and means for creating draft suction pressure therein, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first, but at a higher predetermined suction pressure level, a projectible member for gripping the low pressure valve in closed position, a cylinder, a piston movable in said cylinder, said piston being connected to said projectible member, valve including means connected to said cylinder at the opposite side of said piston from that at which said projectible member extends and adapted to deliver a gaseous

fluid thereto under suitable pressure, means for delivering a gaseous fluid to said cylinder at the end thereof from which said projectile member extends, said last named means including a pressure reducing valve, and a pressure relief valve suitably connected to said gaseous fluid delivering means between said cylinder and said pressure reducing valve, said pressure relief valve being set at a pressure in excess of that delivered by said pressure reducing valve but at a pressure well below that delivered to said cylinder at the opposite side of said piston from that at which said projectile member extends.

16. The combination with a smoke box and means for creating draft suction pressure therein, of valve means adapted to automatically open to admit a suction pressure reducing gaseous fluid, such as air, into said smoke box when the suction pressure therein reaches a predetermined level, and automatically close when said suction pressure drops below said predetermined level, a second valve means constructed for operation in like manner to the first, but at a higher predetermined suction pressure level, a projectile member for gripping the low pressure valve in closed position, a cylinder, a piston movable in said cylinder, said piston being connected to said

projectile member, valve including means connected to said cylinder at the opposite side of said piston from that at which said projectile member extends and adapted to deliver a gaseous fluid thereto under suitable pressure, means for delivering a gaseous fluid to said cylinder at the end thereof from which said projectile member extends, said last named means including a pressure reducing valve, a pressure relief valve suitably connected to said gaseous fluid delivering means between said cylinder and said pressure reducing valve, said pressure relief valve being set at a pressure in excess of that delivered by said pressure reducing valve but at a pressure well below that delivered to said cylinder at the opposite side of said piston from that at which said projectile member extends, and means for automatically controlling the operation of said valve connected for delivery of gaseous fluid to said cylinder at the end thereof opposite to that through which said projecting member extends, whereby the shifting of suction pressure level control from the low pressure inlet to the higher and back is automatically accomplished in accordance with predetermined conditions.

ROBERT R. McINTOSH.

Certificate of Correction

Patent No. 2,377,895.

June 12, 1945.

ROBERT R. McINTOSH

It is hereby certified that errors appear in the printed specification of the above numbered patent requiring correction as follows: Page 2, second column, line 10, for "sectionad" read *sectional*; line 12, for "control" read *controls*; line 40, after "locomotive" insert *smoke*; line 65, for "ajacent" read *adjacent*; page 4, second column, line 70, for "pistons 9a" read *pistons 90a*; and that the said Letters Patent should be read with these corrections therein that the same may conform to the record of the case in the Patent Office.

Signed and sealed this 4th day of March, A. D. 1947.
